COLORADO

BATHTUB CHAIR

Application filed October 7, 1929. Serial No. 397,926.

Our invention relates to bath tub chairs, and more especially to bath tub chairs which are adapted to hang on a bath tub and whose seat is at a higher level than the top of the tub, whereby a person may easily and safely get into and out of the tub by use of the chair, and is an improvement over the invention of Thomas A. Sadusky, whose patent application was filed Feb. 26th, 1929, the Serial Number being 342,892.

The object of this invention is to provide a swiveled chair which, like the Sadusky invention mentioned above, may be easily, quickly and reliably attached to a bath tub, but which because of details of its design and construction is extremely cheap and simple to make, so that it may be sold at a low price, and sales resistance thereby overcome.

A further object is to provide such a chair which is made of separate units all of which are held together as properly assembled, by one wing-nutted bolt.

A further object is to provide such a chair which because of its separate-unit construction, may be assembled with different hanger units, so that by the manufacture of several different designs of hanger-units, chairs may be assembled by the single wing-nutted bolt to fit any bath tub, regardless of its design, construction, wall angle, or thickness.

We attain the above objects by providing a seat, a base properly attached to the seat and in which a shouldered bolt is revolvably mounted, and by providing separate hanger units composed of a hook unit and a brace unit which are to be mounted upon the shouldered bolt and clamped tightly together thereon against the bolt shoulder by a wing nut threadedly mounted upon the bolt.

All of this is described in detail below and is shown in the drawings, in which:—

Figure 1 is a side elevation of our bath tub chair as it would appear when mounted on a bath tub, only a fragment of which is shown.

Figure 2 is an end elevation of our chair and a fragmentary section of the tub shown in Figure 1.

Figure 3 is an end elevation of our chair and a fragmentary section of a different form of bath tub, the hanger units of the chair

being selected to conform to the construction of the tub.

Figure 4 is a fragmentary section of our chair and the hanger units shown in Figure 3.

The seat 1 as shown, is substantially flat and round, for the reason that this provides the cheapest seat that will give satisfactory service, though this chair is not restricted to this particular type and form of seat. Any other proper form and construction of seat may be employed so long as it is properly and securely attached to the base 2.

The base 2 is provided with the flange 3 which permits its attachment to the seat 1 by the screws 4. Any other proper method of securing the seat 1 to the base 2 may be employed, however, so long as it is cheap, reliable and satisfactory.

The base 2 is provided with the hole 5 at the upper end of which is the countersink 6.

The assembly bolt 7 is provided with the head 8, the shoulder 9, the reduced diameter portion 10, and the thread 11.

The distance from the head 8 to the shoulder 9 is greater than from the bottom of the countersink 6 to the bottom of the base 2.

The hook unit is composed of the hook plate 13 and the hooks 14, which are riveted, welded or otherwise properly attached to and made integral with the hook plate 13. The hook plate is provided with a centrally located aperture adapted to receive the portion 10 of the assembly bolt 7.

The hooks 14 are covered by the hook covers 15 of rubber or other proper material that will not injure the surface of the bath tub, and will make noiseless contact therewith.

The brace unit 16 is provided with an aperture to receive the assembly bolt 7 and is bent to form a foot portion 17, which is provided with the contact piece 18, made of rubber or other proper material that will not injure the bath tub and will make noiseless contact therewith.

When the units of the seat are to be assembled, the lower end of the assembly bolt 7 is passed through the plate hook 13 of the plate unit and through the aperture of the

brace unit, and the wing nut 12 is then started upon the bolt 7 and is later tightened to clamp the hook and brace units in place with the hook plate bearing against the shoulder 5 9 of the bolt 7, as will appear below.

The hooks 14 are next placed over the top of the tub 19 and the nut 12 tightened which will cause the brace foot 17 to contact with the wall of the tub and hold the seat in position as shown in Figure 2. The brace 16 10 also contacts with the under edge of the roll of the tub which positively prevents the removal of the seat from the tub.

The bottom of the base 2 will rest upon 15 the hook plate 13, which will space the bolt head 8 from the bottom of the countersink 6 and permit the seat to freely swivel, as shown in Figure 1.

Obviously the brace 16 may be placed upon 20 the bolt 7 below the plate 13, if desired, with no particular change in results.

When a bath tub of different side wall construction or wall angle is encountered, a hook unit and covers having hooks and covers such 25 as shown at 14' and 15' in Figure 3 and with a brace unit 17' and covers 18' may be employed, constructed to fit the particular bath tub in question.

When, as in Figure 3, there is no ledge, 30 shoulder, or roll on the tub, under which the brace may fit to prevent removal of the seat from the tub, the nut 12 may be tightened after the units are assembled and the seat, hook and brace units as a rigid assembly may 35 be mounted upon or taken from the tub without loosening the nut 12.

In such a case the brace foot 17' may have an aperture 17'' in which the upper end of the tie rod 20 may hook. The lower end 21 40 of the tie rod hooks into the screw eye 22, which is screwed into the floor.

The turnbuckle 23 may then be adjusted so the seat will be as solidly held in place as it is by the construction shown in Figures 45 1 and 2.

The lower tie rod end 21 may be anchored in any other proper manner if the screw eye 22 is not used, so long as a strong and reliable fastening for the tie rod is provided.

50 The particular tie rod construction employed and the brace 16' combine to form the brace unit for tubs with straight plain sides and to perform the same functions as are performed by the brace 16 of the rolled top tub construction. That is, the tie rod construction prevents removal of the seat from the tub.

The tie rod construction, however, need not be used unless it is so desired, since its 60 only duty is to hold the seat down upon the tub and is not to furnish support.

But, regardless of the tub upon which the chair is to be mounted, and whether or not the tie rod construction is employed, the same 65 seat, base, bolt and wing nut will be used

in any case, so that only the hook and brace units need be made different for different makes and constructions of tubs.

And in any case when the seat is in use, the assembly bolt and the wing nut act to hold 70 all the units rigidly together to form a strong and reliable seat that will easily swivel, and that can be manufactured at low cost and sold at a low price.

It will be seen that though our new chair does not have the screw mounting of the seat, it still performs the duty permitting a person to get into and out of a bath tub with safety; and the simplified construction and the separate unit design make this chair very 75 attractive from the standpoint of the manufacturer who desires to market a bath tub chair to fit all forms, types, and kinds and constructions of tubs with the least possible expenditure in manufacturing equipment.

It will also be observed that this new design permits the chair to be mounted, if desired inside of the tub, by the provision of the proper hanger units.

Having now described our chair, what we 80 claim as new, and desire to protect by Letters Patent, is as follows:—

1. In a chair adapted to be mounted upon the wall of a bath tub, a seat, a base attached to the seat and having a hole therethrough and forming therewith a seat unit, a headed assembly bolt in the hole of the base and extending downward below the base and provided below the base with a shoulder and a thread, a hook unit provided with spaced 90 hooks adapted to hook over the top of the tub and with a hole adapted to receive the assembly bolt, a brace unit adapted to contact against the wall of the tub below its top and provided with a hole to receive the assembly bolt, and a nut adapted to screw on the assembly bolt and clamp the hook and brace units between itself and said shoulder on the assembly bolt.

2. A bath tub chair adapted to be mounted 110 on a roll top bath tub composed of a pivotally mounted seat unit and a support, the support composed of a hook unit adapted to hook over the top of the wall of the tub and a brace unit adapted to bear against the wall 115 of the tub below the top thereof and to contact the lower face of the said roll top, and an assembly bolt and nut adapted to assemble the three units while permitting free pivotal movement of the seat unit on the support, 120 whereby the brace unit will hold the seat in position and prevent its removal from the tub.

3. A bath tub chair having a pivotally mounted seat and composed of a seat unit and a support, the support being composed of a hook unit adapted to hook over the top of the wall of the tub and a brace unit having means adapted to position the chair against either upward or downward movement, and 130

an assembly bolt and nut adapted to assemble the three units while permitting free pivotal movement of the seat unit on the support.

5 4. In a bath tub chair, the combination of a seat unit having an assembly bolt hole, a hook unit having spaced hooks adapted to hook over the top of the tub, and a brace unit adapted to bear against the wall of the tub 10 below its top, and a shouldered assembly bolt and nut adapted to assemble said units and to clamp the hook and brace units securely together against the shoulder of the bolt while permitting free pivotal movement of 15 the seat unit with respect to the other units.

5. In a bath tub chair adapted to be mounted upon the wall of a bath tub, the combination of means to hook over the top of the tub wall, means to rest against the said wall 20 below its top, a seat having a bolt hole resting upon the two said means, a shouldered headed bolt passing through the hole of the seat and through the two said means and a nut on the bolt to clamp the two said means 25 against the shoulder of the bolt.

6. In a bath tub chair adapted to be mounted upon the wall of a bath tub, the combination of a support formed of an apertured hook unit adapted to hook over the top of the 30 wall of the tub, and an apertured brace unit adapted to bear against the wall of the tub below the top thereof, an apertured seat unit mounted on said support, a shouldered, headed assembly bolt adapted to pass through 35 the apertures of said units and a nut adapted to screw upon the bolt and clamp the hook and brace units against the shoulder of the bolt and pivotally mount the seat unit between the head and the shoulder of the 40 bolt.

7. In a bath tub chair adapted to be mounted upon the wall of a bath tub, the combination of a support formed of a hook unit adapted to hook over the top of the wall of 45 the tub, and a brace unit adapted to bear against the wall of the tub below the top thereof, a seat unit mounted on said support, and a headed, threaded, shouldered assembly bolt provided with a nut and adapted to 50 clamp the hook and brace units securely together between the bolt shoulder and the nut and to provide a free pivotal connection between the seat and the other units intermediate the bolt shoulder and the bolt head.

55 8. In a bath tub chair having a pivotally mounted seat, the combination of a seat unit and a support, the support being composed of a hook unit adapted to hook over the top of the wall of the tub and a brace unit adapted to bear against the wall of the tub below the top thereof, and an assembly bolt and nut adapted to firmly assemble the other two units while permitting free pivotal movement of the seat unit on the support thus 60 formed.

In testimony whereof we affix our signatures.
